UNITED STATES PATENT OFFICE

115,786

DESIGN FOR A LAMP SHADE OR SIMILAR ARTICLE

Harold Goldberg, New York, N. Y., assignor to Abels, Wasserberg & Co., Inc., New York, N. Y., a corporation of New York

Application March 22, 1939, Serial No. 83,756

Term of patent 7 years

To all whom it may concern:

Be it known that I, Harold Goldberg, a citizen of the United States, residing in the city, county, and State of New York, have invented a new, original, and ornamental Design for a Lamp Shade or Similar Article, of which the following is a specification, reference being had to the accompanying drawing, forming part thereof.

In the drawing:

Fig. 1 is a perspective view of the lamp shade or similar article showing my new design; and
Fig. 2 is a perspective view of the opposite side thereof.

I claim:

The ornamental design for a lamp shade or similar article, as shown.

HAROLD GOLDBERG.
